(57) **CLAIM**

The ornamental design for a radio faceplate, as shown and described.

DESCRIPTION

FIG. 1 is a front perspective view of a radio faceplate showing our new design;

FIG. 2 is a front view thereof;

FIG. 3 is a top view thereof;

FIG. 4 is a bottom view thereof;

FIG. 5 is a left side view thereof; and,

FIG. 6 is a right side view thereof.

It will be understood that the dashed lines presented in the drawings are for illustration only, and do not form a part of the claimed design.
